UNITED STATES PATENT OFFICE.

MATTHEW W. RYAN, OF NEW YORK, N. Y.

DESIGN FOR CRETONNE OR OTHER TEXTILE FABRIC.

51,032.

Specification for Design.

Patented July 10, 1917.

Application filed April 27, 1917. Serial No. 165,045. Term of patent 3½ years.

To all whom it may concern:

Be it known that I, MATTHEW W. RYAN, a citizen of the United States, residing in the city of New York, borough of Manhattan, in the county and State of New York, United States of America, have invented a new, original, and ornamental Design for Cretonnes or other Textile Fabrics, of which the following is a specification, reference being had to the accompanying drawings, forming a part thereof, wherein—

The figure is a plan view of a textile fabric illustrating my new design.

What I claim and desire to secure by Letters Patent is:

The ornamental design for a cretonne or other textile fabric consisting of the design substantially as shown.

MATTHEW W. RYAN.
